CLAIM

The ornamental design for an infusion set assembly, as shown and described.

DESCRIPTION

FIG. 1 is a top perspective view of an infusion set assembly showing our new design;

FIG. 2 is a bottom perspective view of the infusion set assembly shown in FIG. 1;

FIG. 3 is a top plan view of the infusion set assembly shown in FIG. 1;

FIG. 4 is a front elevational view of the infusion set assembly shown in FIG. 1;

FIG. 5 is a right side elevational view of the infusion set assembly shown in FIG. 1;

FIG. 6 is a left side elevational view of the infusion set assembly shown in FIG. 1;

FIG. 7 is a rear elevational view of the infusion set assembly shown in FIG. 1;

FIG. 8 is a bottom plan view of the infusion set assembly shown in FIG. 1; and,

FIG. 9 is a cross-sectional view of the infusion set assembly shown in FIG. 1, taken along the line 9-9 of FIG. 3.

The ornamental design that is claimed is shown in solid lines in the drawings. The broken lines in the figures represent portions of the infusion set assembly that form no part of the claimed design.
